D. H. BRAZIL.

CUT-OFF VALVE.

APPLICATION FILED JULY 26, 1916.

1,235,104.

Patented July 31, 1917.

UNITED STATES PATENT OFFICE.

DAVID HARTWELL BRAZIL, OF MONTGOMERY, ALABAMA, ASSIGNOR OF ONE-FOURTH
TO WILLIAM PORTER SANDWICH, OF MONTGOMERY, ALABAMA.

CUT-OFF VALVE.

1,235,104.

Specification of Letters Patent.

Patented July 31, 1917.

Application filed July 26, 1916. Serial No. 111,460.

To all whom it may concern:

Be it known that I, DAVID HARTWELL BRAZIL, a citizen of the United States, residing at Montgomery, in the county of 5 Montgomery and State of Alabama, have invented certain new and useful Improvements in Cut-Off Valves; and I do hereby declare the following to be a full, clear, and exact description of the invention, such as will 10 enable others skilled in the art to which it appertains to make and use the same.

This invention relates to dispensing cans, and more especially to rotary cut-off nozzles which are vented; and the object of the 15 same is to produce a nozzle or spout of this character rotatably mounted within the nipple of a can or other container, carrying its own vent, and bodily and quickly removable so that the can may be filled. The following specification sets forth several embodiments of the idea, in one of which devices are provided for preventing the rotation of the seat as the base plate of the spout turns thereover. In the drawings—

25 Figure 1 is a vertical sectional view of what might be called my preferred form, Fig. 2 is a plan view thereof, Fig. 3 is a bottom plan view of the seat plate, and Fig. 4 is a top plan view of a portion of the can body and the whole of its nipple, with the 30 detachable members removed.

Throughout the various views the can body B is shown as having an opening in its top, and to the latter is secured the usual 35 nipple N which is herein illustrated as threaded. The cap is designated by the letter C and herein shown as screwing onto the nipple N, and the pouring spout is lettered S. No novelty is claimed for the parts 40 thus far described.

In the type of my invention shown in the views (and in which the nipple is upstruck from the top of the can body instead of being soldered thereto, although this detail is 45 unimportant) the open upper end or mouth of the nipple is bent inward and corrugated as at 9, and the same gasket and cap are employed as above described. The down-turned inner end of the spout S is secured 50 upon a disk or plate 41 around an opening 43 therein. The seat consists of a disk or base plate 45 of a size to fit rotatably within the cap and with its edge 3' resting upon the

gasket 2', its wall 4' being bent upward and inward into a flange 42 overlying the washer 40, and both this plate and its washer are provided with a pouring opening 46 and a vent opening 47 as best seen in Fig. 3. Rigidly depending from the plate around the vent opening is a vent tube 44, preferably 60 of a length to extend completely through the nipple and into the body of the can. Depending rigidly from the plate 45 near its edge is a flange 48 which is of a size to pass into the upper end of the nipple, and this 65 flange also is corrugated to fit the corrugations 9 of the nipple when the parts are assembled. The operation is the same as above described, and the turning of the spout moves its plate 41 over the washer so as to 70 throw the holes into or out of register as desired. Meanwhile the corrugations in the flange 48 which are in constant engagement with the corrugated nipple present a rotary movement of the seat within the nipple. In 75 this case the rotary member is pressed down onto the seat to the extent that the cap is tightened on the nipple. The parts are of the desired size and shape, proportions, and materials, and modifications are possible 80 within the scope of the claims below.

What I claim is:

1. A dispensing container having a threaded discharge nipple with an inturned flange on its upper end, the edge of which is 85 corrugated, a disk overlapping said flange and having a pouring aperture and a vent opening, said disk having a depending flange corrugated to interlock with the corrugated edge of the flange, packing surrounding the 90 flange and clamped between the disk and flange, a plate above the disk having a pouring nozzle and a vent opening to register with respective openings in said disk, packing between said plate and disk and secured 95 to the latter, and a flanged screw cap for engaging the nipple and turnably securing the nozzle plate in position.

2. A dispensing container having a threaded discharge nipple with an inturned 100 flange on its upper end, the edge of which is corrugated, a disk overlapping said flange and having a pouring aperture and a vent opening, said disk having a depending flange corrugated to interlock with the corrugated edge of the flange, packing sur-

rounding the flange and clamped between the disk and flange, a plate above the disk having a pouring nozzle and a vent opening to register with respective openings in said 5 disk, packing between said plate and disk and secured to the latter, and a flanged screw cap for engaging the nipple and turnably securing the nozzle plate in position, said

disk having an inturned bead clenching the edge of the packing thereon.

In testimony whereof I affix my signature in presence of two witnesses.

DAVID HARTWELL BRAZIL.
